(57) **CLAIM**

The ornamental design for a packaging insert for a process chamber component, as shown and described.

DESCRIPTION

FIG. 1 is a top isometric view of a packaging insert for a process chamber component.

FIG. 2 is a top plan view thereof.

FIG. 3 is a bottom plan view thereof.

FIG. 4 is a front elevation view thereof.

FIG. 5 is a back elevation view thereof.

FIG. 6 is a right side elevation view thereof.

FIG. 7 is a left side elevation view thereof; and,

FIG. 8 is a cross-sectional view taken along line 8-8 of FIG. 2.

The broken lines in FIGS. 1, 2, and 8 show portions of a packaging insert for a process chamber component that form no part of the claim.

1 Claim, 5 Drawing Sheets
